CARD PUNCH AND DIE ASSEMBLY

Hunter E. Hooe, Athens, Ohio, assignor to The
McBee Company, Athens, Ohio, a corporation

Application April 11, 1949, Serial No. 86,818

8 Claims. (Cl. 164—11)

1

This invention relates to a card punch and die assembly adapted to punch notches and slots in marginally perforated cards.

Cards of the character referred to, such as the well known "Keysort" cards, are provided with marginal perforations including an outer row of perforations and an inner row of perforations. These perforations are also grouped into fields or classes, each field comprising, for example, four perforations, three of which are arranged in an outer row and one in an inner row and corresponding to the numerals "0," "1," "2," "4," and "7." By notching these cards to an inner or outer row of perforations and/or by slotting them to provide a slot extending from an inner perforation to an outer perforation but short of the edge of the card, the cards are coded. Rapid selection of the coded cards from among a large number thereof is possible.

It is an object of the present invention to provide an improved form of punch and die assembly for marginally punching and slotting cards of the character described.

It is a further object of the present invention to provide a card punch and die assembly which is operable manually or by a key-operated mechanism, to punch shallow notches to outer perforations, deep notches to inner perforations or slots extending from an inner perforation to an outer perforation but short of an edge of the card.

These and other objects of the invention will be apparent from the ensuing description and the appended claims.

One form which the invention may assume is exemplified in the following description and illustrated by way of example in the accompanying drawings, in which:

Fig. 1 is a side elevation of the card punch and die assembly showing a card in place therein.

Fig. 2 is an end elevation of the same as seen from the left of Fig. 1.

Fig. 3 is a fragmentary view showing operation of the punching mechanism to form a shallow notch.

Fig. 3a is a fragmentary view of a marginally perforated card showing the same after it has been punched to provide a shallow notch.

Fig. 4 is a view similar to that of Fig. 3, but showing the operation of the punching mechanism to punch a slot.

Fig. 4a is a view similar to Fig. 3a, but showing a card punched to provide a slot.

Fig. 5 is a view similar to Fig. 3, but showing operation of the punching mechanism to punch out a deep notch.

Fig. 5a is a view similar to that of Figs. 3a and 4a, but showing a card with a deep notch punched therein.

Referring now to the drawings, a punch generally designated as 10 is shown as punching a marginally perforated card generally designated as 11, such card having an outer row of perforations 12 and an inner row of perforations 13.

2

The object of the punching is to punch out one or more shallow notches 14 (see Fig. 3a) extending from an edge of the card to an outer perforation 12, or a slot 15 (see Fig. 4a) extending from an inner perforation 13 to an outer perforation 12, or a deep notch 16 (see Fig. 5a) extending from an edge of the card to an inner perforation 13.

The punch mechanism 10 comprises a pair of die blocks 25 and 26 mounted on a base 27, as by means of screws 28. The die blocks 25 and 26 are formed with beveled inner edges 29 and 30, respectively, and with transverse recesses 31 and 32, respectively. As will be seen, the die blocks 25 and 26 are spaced apart slightly to provide a card feed slot 33, and the transverse passages 31 and 32 form a rectangular passage or opening 34 for a purpose explained hereinafter.

The die blocks 25 and 26 are also formed with aligned longitudinal passages 35 and 36, to receive a plurality of lower punches 40 and, as illustrated, a single upper punch 41. Obviously, the passages 35 and 36 may be formed to receive any desired number of punches 40 and 41. As illustrated, the punches 40 and 41 are provided at their rear ends with holes 42 to receive pins, rods or any other mechanical connection (not shown) for actuating the punches manually, mechanically or electrically. Each lower punch 40 is formed with an oblique shearing edge 43 spaced from an abutment surface 44 and it is also formed with a circular opening 45. The openings 45 are normally in alignment with each other and with the rectangular opening 34 formed in the die blocks. The upper punch 41 is formed with an oblique cutting edge 46.

It will be understood that any suitable form of mechanism may be provided for actuating the lower and upper punches 40, 41, either manually or by a key-operated mechanism. Such means of actuating the punches are well known in the art, form no part of the present invention and require no description here.

In operation, as shown in Figs. 3 and 3a, if it is desired to form a shallow notch 14 extending from an edge of the card 11 to an outer perforation 12, the card is inserted in the punching mechanism as illustrated in Figs. 1 and 2, and the appropriate lower punch 40 is actuated to cause movement thereof in the direction indicated by the arrow. The punch 40 thus shears the card and forms a chip 50 which drops into the circular opening 45, thence into the rectangular opening 34 formed in the die blocks, from which the accumulation of chips may be removed from time to time. During this operation, a die or guide is formed for guiding the travel of the lower punch 40, by the side or sides of the adjacent punch or punches 40 and by the adjacent walls of the die blocks 25 and 26. In the case of the right-hand punch 40 (as viewed in Fig. 2), which is aligned with the upper punch 41, the

undersurface of the latter also serves as a die surface for the lower punch.

More particularly, it will be seen that each lower punch 40 is formed with a cutting edge having straight portions 50a and concave portions 51, and that the longitudinal passages 35 and 36 formed in the die blocks have a complementary shape, including convex portions 52 and fingers 53 having convex edges 54. It will thus be apparent that whenever a lower punch 40 is caused to move, a die for guiding its movement and ensuring a proper punching of the card is provided by the punches themselves and by the die blocks.

Referring now to Figs. 4 and 4a, when it is desired to punch out a slot 15 extending from an inner perforation 13 to an outer perforation 12, the upper punch 41 is actuated, being moved in the direction indicated by the arrow in Fig. 4. The punch 41 punches out a chip 55, which is carried forwardly so as to fall out of the way. During its travel, the upper punch 41 is guided and a die is formed therefor, by the upper surface of the adjacent lower punch 40 and the adjacent walls of the die blocks 25 and 26. Also, the surface 43 of the adjacent lower punch 40 provides a backing for the card 11 to hold it firmly in position.

Referring now to Figs. 5 and 5a, if it is desired to form a deep notch 16 extending from an edge of the card to an inner perforation 13, such is accomplished by actuating both the upper punch 41 and the adjacent lower punch 40, moving the same oppositely as indicated by the arrows in Fig. 5, and preferably simultaneously, so as to punch out chips 50 and 51 and form the desired deep notch.

It is thus apparent that a card punch and die assembly has been provided which is operable to punch shallow notches, deep notches or slots in marginally perforated cards; which is simple in its construction and operation; and which, among other advantages, is characterized by the fact that the punches themselves are so disposed and arranged that they function as dies for guiding each other.

While I have illustrated and described my invention in detail, it is to be understood that various changes may be made therein by those skilled in the art without departing from the spirit of the invention as defined in the appended claims.

Having thus described my invention, what I claim and desire to secure by Letters Patent is:

1. A punch and die assembly comprising a die block having a card-receiving passage formed therein, a plurality of shallow punches reciprocably disposed in said block in side-by-side relationship such that when one of said punches is actuated to punch a shallow notch in a card one or more adjacent shallow punches provide surfaces for guiding the punch which is being actuated, and one or more slot punches also reciprocably disposed in said die block, each said slot punch being adjacent a shallow punch such that the adjacent shallow punch provides a guide surface for said slot punch, said slot punch and the adjacent shallow punch being operable together to punch a deep slot in a card.

2. A punch and die assembly for punching and slotting marginally perforated cards to code the same comprising: a die block formed with a card-receiving slot, an opening for chips, a first punch passage and a second punch passage; a plurality of shallow punches slidably received within

said first passage and arranged in side-by-side relationship; a slot punch slidably received in said second passage and in sliding contact with the upper surface of one of said shallow punches; said shallow punches being so arranged that when one of them is actuated the wall or walls of adjacent shallow punch or punches serve as dies to guide the active punch; said slot punch being so arranged that when it is actuated the adjacent shallow punch and adjacent walls of said second passage form a die for guiding the same, and that simultaneous operation of said slot punch and the adjacent shallow punch operate to punch a deep notch in a card.

3. A punch and die assembly comprising a base; a pair of die blocks mounted on said base in spaced relationship to provide a card feed slot; said die blocks being formed with a transverse chips opening and with aligned longitudinal passages including a lower portion to receive a plurality of lower punches and an upper portion to receive one or more upper punches; a plurality of lower punches slidably disposed in said lower portion in side-by-side relationship such that each serves as a die for adjacent punches, each said lower punch being formed with a cutting edge disposed intermediate the ends of the die, an abutment surface spaced from said cutting edge and chips passage for communicating with said chips opening; and one or more upper punches slidably disposed in said upper portion in sliding contact with the upper surface of a lower punch.

4. A punch and die assembly comprising a pair of oppositely disposed, cooperating die members forming a work-receiving slot and a communicating punch-receiving slot, a first punch having a cutting edge intermediate its ends, said punch being mounted in said punch-receiving slot and movable through said work-receiving slot to cut work in a first area, and a second punch mounted in said punch-receiving slot movable through said work-receiving slot to cut work in a second area.

5. The structure set forth in claim 4 in which the punches are in juxtaposed sliding relation.

6. The structure set forth in claim 4 in which the punches have contiguous cutting surfaces.

7. The structure set forth in claim 4 in which the cutting surface of one punch is in opposition to the cutting surface of the other punch, whereby the cutting movements of the punches are in opposite directions.

8. A punch and die assembly comprising a die member having a work-receiving slot and a communicating punch-receiving slot, a first punch mounted in said punch-receiving slot movable through said work-receiving slot to cut work in a first area, and a second punch mounted in said punch-receiving slot movable through said work-receiving slot to cut work in a second area, the cutting surface of one punch being in opposition to the cutting surface of the other punch and the punches being independently movable in opposite directions for cutting their respective areas.

HUNTER E. HOOE.
